UNITED STATES PATENT OFFICE

99,471

DESIGN FOR A WATER SPRINKLER

Horace C. Wright, Chicago, Ill., assignor to Chicago Flexible Shaft Company, Chicago, Ill., a corporation of Illinois

Application August 12, 1935, Serial No. 58,086

Term of patent 7 years

To all whom it may concern:

Be it known that I, Horace C. Wright, a citizen of the United States, residing at Chicago, in the county of Cook and State of Illinois, have invented a new, original, and ornamental Design for a Water Sprinkler, of which the following is a specification, reference being had to the accompanying drawing, forming part thereof.

In the drawing:

The figure is a side perspective of the sprinkler

body showing my design, the opposite side of the sprinkler being substantially like the side shown except that the socket member is omitted on said opposite side.

The dominant feature of the design resides in the portions shown in full lines.

I claim:

The ornamental design for a water sprinkler substantially as shown and described.

HORACE C. WRIGHT.
